CLAIM

The ornamental design for a wireless sensor system, as shown and described.

DESCRIPTION

FIG. 1 is a perspective view of a wireless sensor system showing a first embodiment of the new design;

FIG. 2 is a top view of the first embodiment of the wireless sensor system of FIG. 1;

FIG. 3 is a bottom view of the first embodiment of the wireless sensor system of FIG. 1;

FIG. 4 is a front view of the first embodiment of the wireless sensor system of FIG. 1;

FIG. 5 is a rear view of the first embodiment of the wireless sensor system of FIG. 1;

FIG. 6 is a left side view of the first embodiment of the wireless sensor system of FIG. 1; and,

FIG. 7 is a right side view of the first embodiment of the wireless sensor system of FIG. 1.

The broken lines depict unclaimed portions of the wireless sensor system and form no part of the claimed design.
